16 Claims. (Cl. 260—462)

This invention concerns processes for the production of alkyl boric acid esters and free alkyl boric acids.

It has long been known to obtain alkyl boric acid esters of the general formula $RB(OR)_2$, in which R represents a hydrocarbon radical, by the use of alkylation agents, such as for example Grignard compounds or zinc alkyls, from boric acid esters of the general formula $B(OR)_3$, in which R is likewise a hydrocarbon radical. Alkyl boric acid esters have also been successfully produced by the oxidation of boron trialkyls using dry air. In this case one or two alkyl groups on the boron atom are transformed into the corresponding alkoxy groups.

Since boron trialkyls of the general formula BR_3 , in which R represents an aliphatic hydrocarbon radical, can in these days easily be obtained by simple manufacturing processes, more especially by using aluminium trialkyls, these aliphatic boron hydrocarbons BR_3 are also suitable from an economic point of view for further processing to produce alkyl boric acid esters or free alkyl boric acids. The manufacture of alkyl boric acid esters by oxidation, likewise starting from the boron trialkyls, is uneconomical because of the loss of one or two valuable alkyl groups.

It has now been found to be possible to manufacture alkyl boric acid esters from boron trialkyls in a very simple manner while maintaining all boron-carbon bonds therein. The present invention is concerned with the reaction of boron trialkyls with boric acid esters to form alkyl boric acid esters in good yields in accordance with the following general equations:

or

in which R and R' represent hydrocarbon radicals which can be the same or different.

The reaction according to the invention was not in any way to be expected since, according to the data given in technical literature, previously experiments which were to have led to the reaction of boron alkyls with boric acid esters produced negative results (cf. H. Meerwein, H. Sönke, J. Pr. Chem. 147, 252 (1936)). This reaction can, however, easily be carried out successfully in accordance with the invention.

According to the invention, a boron trialkyl of the general formula BR_3 , in which R represents an aliphatic hydrocarbon radical, is heated with a boric acid ester of the general formula $B(OR')_3$, in which R' represents an aliphatic hydrocarbon radical, to a temperature exceeding $100^\circ C.$, and advantageously to $200^\circ C.$ or higher. Irrespective of the molar ratio which is employed, a monoalkyl boric acid ester is generally formed.

The dialkyl boric acid monoalkyl ester formed in the first stage of the reaction is generally further converted with disproportionation under the conditions of the reaction, in accordance with the equation:

so that in such cases unconverted trialkyl boron is left as well as a monoalkyl boric acid ester. Consequently, if the quantity of boric acid ester is too low when carrying

2

out the process, this is generally shown by a correspondingly smaller conversion of the boron alkyl to monoalkyl boric acid ester. With an excess of boric acid ester in relation to the boron trialkyl the excess quantity of boric acid ester is recovered, in addition to the alkyl boric acid ester. Advantageously, for the production of a monoalkyl boric acid ester, a mixture of 1 mol of a boron trialkyl is heated with 2 mols of a boric acid ester, possibly in a pressure vessel, to temperatures between 200 and $250^\circ C.$, the corresponding monoalkyl boric acid ester being formed in a substantially quantitative yield. A subsequent distillation is not absolutely necessary.

When carrying out the process according to the invention, it is advisable to work without solvents so that the alkyl boric acid ester can be obtained directly in a pure form. It is, however, possible to use certain solvents. All saturated aliphatic and aromatic hydrocarbons are suitable for this purpose and it is possible to use ethers as solvents. The use of solvents is particularly advisable when using solid starting materials or when solid products are formed.

From the alkyl boric acid esters which can be produced by the process of the invention, it is possible to obtain the free alkyl boric acids in a known manner by reaction with water. The B-alkyl boroxols are formed from the monoalkyl boric acids by splitting-off water. Alkyl boric acid esters are of importance as additives to engine fuels.

The following examples further illustrate the invention:

Example 1

A mixture of 70 g. (0.5 mol.) of boron tri-n-propyl and 104 g. (1 mol) of trimethyl borate is placed under nitrogen in a 500 cc. autoclave, which is heated while shaking for 2-3 hours at $250^\circ C.$, pressures up to a maximum of 30 atm. being reached. After cooling, the colourless liquid is emptied out. By distillation, and after a small quantity of first runnings, 150 g. of monopropyl boric acid dimethyl ester with a boiling point of $102-103^\circ C.$ are obtained. The benzoic peracid value of the compound corresponds to that of one alkyl group on the boron.

Example 2

A mixture of 175 g. (0.5 mol) of pure boron tri-n-octyl and 292 g. (2.0 mol) of triethyl borate is heated for 10 hours at $200^\circ C.$ in a 1-litre autoclave. The colourless discharged is thereafter distilled. 150 g. of unmodified triethyl borate (B.P. 16/17 mm. = $29-30^\circ C.$) are obtained as first runnings. The mono-octyl boric acid diethyl ester which is formed boils at $70-75^\circ C.$ under a pressure of 2 mm. Hg. A total of 230 g. (=72% of the theoretical) is obtained. The benzoic peracid value of the compound indicates a boron-carbon bond in the molecule.

Example 3

A mixture of 104.5 g. (0.393 mol) of boron tri-n-hexyl and 28.7 g. (0.197 mol) of triethyl borate is heated for 3-4 hours at $210-220^\circ C.$ The mixture is thereafter distilled through a column at reduced pressure. As first fraction (boiling point $72-73^\circ C./8$ mm. Hg.) 45 g. of n-hexyl boric acid diethyl ester (M.P. = $-48^\circ C.$) $n_{D}^{20} = 1.4084$, are obtained. After a small quantity of intermediate runnings (about 5 g.) unreacted tri-n-hexyl boron is left as residue.

3

Example 4

62.4 g. (0.198 mol) of tri-n-hexyl borate and 42.8 g. (0.437 mol) of boron triethyl are heated for 10 hours at 230–240° C. in a 200 cc. autoclave. The liquid (103 g.) is emptied out and distilled in a column, the following fractions being obtained:

- (1) 15.5 cc. of unreacted boron triethyl (B.P.₁₀₋₂₀ = <20° C.).
- (2) B.P.₈=69–70/1° C.; 53 cc. of diethyl boric acid hexyl ester.
- (3) B.P._{0.1}=20–63° C.; 1.5 cc. of intermediate runnings.
- (4) B.P._{0.1}=63–65° C.; 40 cc. of monoethyl boric acid di-n-hexyl ester.

Example 5

73.6 g. (0.277 mol) of boron tri-n-hexyl and 20.1 g. (0.137 mol) of triethyl borate are heated for about 6–7 hours at 240° C. in a closed vessel. The discharged liquid is distilled under reduced pressure and the following fractions are obtained:

- (1) B.P._{0.07-0.08}=30–40° C.; 9 cc.
- (2) B.P._{0.07-0.08}=40–64° C.; 21 cc.
- (3) B.P._{0.07-0.08}=62–64° C.; 18 cc. of di-n-hexyl boric acid monoethyl ester with a melting point (indefinite) of –58 to –45° C.
- (4) A residue consisting mainly of unreacted trihexyl boron (55 cc.).

From the first two fractions, on being redistilled with the use of a highly effective column, monohexyl boric acid diethyl ester of B.P.₁₉=89–90° C. (M.P.=–48° C.; $n_D^{20}=1.4084$) is obtained in pure form after a small quantity of first runnings.

Example 6

202 g. (1 mol) of a glass-like boric acid glycol ester (prepared from 70 g. of boron trioxide and 186 g. of anhydrous glycol) are mixed with 200 g. (1.43 mol) of boron tri-n-propyl. The mixture is heated and, with an internal temperature of 140–160° C. (reflux), the boric acid ester gradually dissolves in the boron alkyl. A colourless liquid (B.P.=126–130° C.) distils into the receiver. Finally, all the liquid is distilled off under reduced pressure and no residue is left. The liquid is rectified in a 40 cm. filler body column. After a small quantity of first runnings, 278 g. (about 300 cc.) of pure mono-n-propyl boric acid glycol ester (B.P.=127° C., B.P.₁₈₀=85° C.; $n_D^{25}=1.4054$, $d_4^{25}=0.9225$) with a boron content of 9.5% are obtained. 70 g. of unreacted boron tripropyl are recovered.

Example 7

434 g. (1 mol) of boron tri-n-decyl are heated for 4–5 hours with 260 g. (2.5 mols) of trimethyl borate to 240–280° C. in a 1 litre autoclave. A colourless liquid is obtained, the distillation of which yields mono-n-decyl boric acid dimethyl ester (B.P.₂₀=125–130° C.; B.P._{0.08}=51–52° C., $n_D^{25}=1.4246$, $d_4^{25}=0.8398$), after first runnings (70 g. of excess trimethyl borate of B.P.=68–69° C.). As residue, 40 g. of unreacted boron-n-decyl are obtained. With quantitative yield, the conversion to mono-n-decyl boric acid dimethyl ester (575 g.) amounts to 90% of the theoretical.

4

Example 8

343.5 g. (0.5 mol) of boron-tri-n-hexadecyl (M.P. = 28–30° C.) are dissolved in 200 cc. of hexane; 130 g. of trimethyl borate are added to this solution. The mixture is heated in a 1-litre autoclave for 6 hours at 220–240° C. After cooling and distilling off the solvent together with the excess trimethyl borate, a colourless readily mobile liquid is obtained, the distillation of which, under reduced pressure (B.P._{0.1}=105–106° C.), produces 375 g. (85% conversion with quantitative yield) of mono-n-hexadecyl boric acid dimethyl ester, $n_D^{25}=1.4378$, $d_4^{25}=0.8349$. The residue (50 g. of boron tri-n-hexadecyl) solidifies slowly on cooling.

Example 9

130 g. (0.5 mol) of boron tricyclohexyl (M.P.=118° C.) are dissolved in 250 cc. of cyclohexane with heating. 125 g. (1.2 mols) of trimethyl borate are added and the mixture is placed in a 1-litre autoclave, which is heated for 6 hours at 220–250° C. After cooling, the excess trimethyl borate is distilled off together with the solvent. Under reduced pressure, 185 g. (80% conversion with quantitative yield) of monocyclohexyl boric acid dimethyl ester (B.P.₁₆=70–71° C., $n_D^{25}=1.4359$, $d_4^{25}=0.9183$) are obtained.

What I claim is:

1. Process for the production of alkyl boric acid esters which comprises heating a boron trialkyl of the general formula BR_3 , wherein R represents a saturated aliphatic hydrocarbon radical with a boric acid ester selected from the group consisting of boric acid glycol esters and esters of the general formula $B(OR')_3$, wherein R' represents a saturated aliphatic hydrocarbon radical, which radical may be the same as the saturated aliphatic hydrocarbon radical designated R, to a temperature in excess of 100° C. and recovering said alkyl boric acid ester.
2. Process according to claim 1, which comprises effecting the heating at a temperature in excess of 200° C.
3. Process according to claim 1, which comprises heating 1 mol of said boron trialkyl with 2 mols of said boric acid ester to from 200 to 250° C.
4. Process according to claim 1, which comprises subjecting said reaction mixture following said heating to distillation.
5. Process according to claim 1, which comprises, in those instances where at least one component of the reaction mixture is a solid, effecting the reaction in the presence of a solvent.
6. Process according to claim 5, wherein said solvent is a member selected from the group consisting of aliphatic hydrocarbons, aromatic hydrocarbons and ethers.
7. Process according to claim 1, which comprises effecting the reaction in a pressure vessel.
8. Process according to claim 1, wherein the compound designated BR_3 is boron tri-n-propyl and the compound designated $B(OR')_3$ is trimethyl borate.
9. Process according to claim 1, wherein the compound designated BR_3 is boron tri-n-octyl and the compound designated $B(OR')_3$ is triethyl borate.
10. Process according to claim 1, wherein the compound designated BR_3 is boron tri-n-hexyl and the compound designated $B(OR')_3$ is triethyl borate.
11. Process according to claim 1, wherein the compound designated BR_3 is boron triethyl and the compound designated $B(OR')_3$ is tri-n-hexyl borate.
12. Process according to claim 1, wherein the compound designated BR_3 is boron tri-n-propyl and said ester is boric acid glycol ester.
13. Process according to claim 1, wherein the com-

pound designated BR_3 is boron tri-n-decyl and the compound designated $B(OR')_3$ is trimethyl borate.

14. Process according to claim 1, wherein the compound designated BR_3 is boron tri-n-hexadecyl and the compound designated $B(OR')_3$ is trimethyl borate.

15. Process according to claim 1, wherein the compound designated BR_3 is boron tricyclohexyl and the compound designated $B(OR')_3$ is trimethyl borate.

16. Process for the production of alkyl boric acid esters capable of conversion by hydrolysis to free alkyl boric acids which comprises heating a boron trialkyl having the general formula BR_3 in which R represents a saturated aliphatic hydrocarbon radical with a boric acid ester selected from the group consisting of boric glycol esters and esters of the general formula $B(OR')_3$ in which R' 15

represents a saturated aliphatic hydrocarbon radical which may be the same as the saturated aliphatic hydrocarbon radical designated R, to a temperature in excess of 100° C. to thereby form a boric acid ester capable of hydrolysis to form the free acid.
